UNITED STATES PATENT OFFICE.

RICHARD E. BROCK, OF CANTON, OHIO.

TUBE-REDUCING MILL.

1,211,070.

Specification of Letters Patent. Patented Jan. 2, 1917.

Application filed February 21, 1916. Serial No. 79,587.

To all whom it may concern:

Be it known that I, RICHARD E. BROCK, a citizen of the United States, residing at Canton, in the county of Stark and State 5 of Ohio, have invented certain new and useful Improvements in Tube-Reducing Mills, of which the following is a specification.

My invention relates to an improved mill for rolling seamless tubing.

- 10 The object of the invention is to provide rapid and efficient means for manufacturing seamless tubing, in which the blank may be continuously treated by a series of reverse rolling operations, under a single heat, back 15 and forth between the same set of cross rolls, whereby to treat it successively in a rapid, practically continuous manner, without the necessity of manual handling of the tube in process.
- 20 Other objects of the invention are to provide means whereby the operation of piercing, reducing and smoothing the walls of the pierced tube or blank, to either increase or decrease the diameter and accurately 25 gage the size of the tube by successive operations, may be quickly and efficiently performed.

Generally stated, the mechanism comprises means for introducing the blank, 30 either solid, when the piercing operation is utilized, or in the form of a hollow blank for successive treatment and finishing, in connection with a suitable mandrel and pushing mechanism, between a pair of cross 35 rolls so mounted as to provide for the reversal of the position for each alternate pass. Also means for guiding the blank in its progress toward and from the cross rolls; means for reversing the blank and reintroducing it between the rolls by the same end 40 which was last treated; means for retaining the blank between the rolls, and for adjusting such retaining means; means for adjusting the cross rolls themselves, and for 45 swivelly mounting and tilting them; and various other features and details of construction as shall be more fully hereinafter described.

In carrying out the manufacture of seam- 50 less tubing by my improved mechanism, it

is essential that the cross rolls shall be quickly reversed, thereby correspondingly reversing the feed of the blank or tube in process, whereby it can be passed back and forth until the several required operations 55 are performed without loss of time or necessity of attendant labor, the various adjustments being quickly and easily performed, certain of such adjustments being made independent of others, under the control of 60 the operator.

In the drawings, which illustrate one preferred embodiment of the invention,—Figure 1 is a view showing the cross rolls in operative position in their housing frame, 65 and the driving mechanism therefor, at one side of the frame. Fig. 2 is a plan view, partly in section, of Fig. 1. Fig. 2^a is a detail plan view showing the blank pushing mechanism at each side of the cross roll. 70 Fig. 3 is a cross sectional detail view, indicated by the line III. III. of Fig. 1. Fig. 4 is an enlarged plan view of the cross roll housing and the accompanying adjusting and actuating mechanism for the several 75 parts. Fig. 5 is a sectional elevation of the cross roll housing frame and the several parts, partly in section, indicated by the section line V. V. of Fig. 4. Fig. 6 is a vertical cross section through the cross roll housing 80 frame, certain parts being omitted, and indicated by the section line VI. VI. of Fig. 5. Fig. 7 is a similar view, indicated by the section line VII. VII. of Fig. 5. Figs. 8, 9, 10 and 11 are diagrammatic sectional detail 85 views illustrating successive steps of operation.

In the operation of rolling by my improved mechanism, the blank, whether solid as originally pierced, or hollow, either with 90 or without a mandrel, is designed to be passed horizontally between two cross reducing rolls 2, 2, arranged for operation at opposing angles, as is usual in cross rolling, but mounted by their journals 3 at each end 95 in bearings 4, 4, of a tilting frame 5, one for each cross roll. Each of said tilting frames is pivotally mounted, as by a stud or gudgeon 6 extending sidewise of the middle portion of the frame and of the cross roll, in 100

2 a slidable carrier frame or cross head 7. Each of said cross heads 7 is slidably mounted by its base upon the upper faces 8 of the lower main cross members 9, 9, of the main housing frame, which itself is mounted upon the foundation members 10 of the mill. Each frame 7 is likewise mounted at its upper portion slidably in runways 11 of the upper main side members 12 of the main horizontal frame, by which means frame 7 is capable of being moved inwardly or outwardly toward or from the working pass of the blank, indicated at *a*, Fig. 5.

5 Each tilting frame 5 is provided at its upper portion with a segmental toothed rack 13, 13', engaging a worm 14, 14' of shaft 15 journaled in bearings 16, 16; and 16', 16', mounted upon and slidable with the sliding frame 7.

10 Shaft 15 is provided at one end with a beveled gear 17 engaging a driving bevel 18 slidably mounted on a splined or squared shaft 19 having a rotatable bushing 20 revolving within a bearing 21 at one edge

15 portion of frame 7. Shaft 19 is journaled at its other end in a bearing 22 extending outwardly from the main housing frame side member 23, and is provided with a toothed gear wheel 24 engaging a driving pinion 25 on shaft 26. Said shaft is journaled in bearings 27, 27, of a bracket 28 supporting a driving motor 29, the pinion 30 of which engages gear wheel 31 mounted on the other end of shaft 26. By this means

20 it will be seen that upon driving the motor 29 in one direction or the other, at whatever position frame 7 may be located toward or from the central pass of the mill, worm 14 will be correspondingly actuated, throwing tilting frame 5 in one direction or the other and positioning the cross roll 2 correspondingly at the proper inclination. It will be understood that the other companion cross roll 2, being constructed and mounted in

25 the same manner and provided with similar actuating mechanism, is arranged to operate simultaneously with the cross roll just described, through its similar mechanism, but in the opposite direction. For such purpose, the shaft 19 is extended over to the other side, and by a bevel gear 18' engaging a bevel gear 17', similar to bevels 18 and 17, but operating as to bevel 17' in the reverse direction, worm 14' at the other side of the

30 center engaging segmental gear teeth 13' of the opposite tilting frame 7, will effect the desired movement. By this means, each tilting frame is alternately actuated in the opposite direction, changing the inclination of 35 the cross rolls with relation to each other, it being understood that the cross rolls are continuously driven in the same direction.

Frame 7 is provided on the upper side of its base with a bearing shoe 32, against 40 which rides a co-acting bearing shoe 33 of

the tilting frame 5, said shoes meeting by their arc-shaped faces defined by a radius struck from the axial center of the tilting frame trunnion. By this means the bearing shoes provide a positive support for the frame at its various positions, the stationary shoe 32 and movable shoe 33 each being fixedly connected with the frame base and tilting frame respectively. Tilting frame 5 is also provided with limiting abutments 44, 44, adapted to engage limiting bearing faces 35, 35, respectively of the frame 7, so as to positively terminate the tilting action in either direction. Any suitable commutator or controlling mechanism for motor 29 may be utilized whereby to control its operation within the desired periods necessary to actuate the tilting frame alternately to the desired degree, as will be readily understood. It will be also understood that 45 each of the cross rolls 2 is driven in the same direction continuously, as stated, and as indicated in the diagrammatic views, Figs. 8 to 11 inclusive.

50 The journal of each cross roll 2 is provided with a coupling terminal 36 having a universal joint bearing socket 37 engaged by an interfitting terminal 38 of a driving shaft 39, one such shaft and coupling terminal being provided for each cross roll, as 55 shown in Figs. 1 and 2.

55 Each of shafts 39 is provided at its opposite end with a similar coupling terminal 40 in universal joint connection with coupling terminal 41 of driving shaft 42, each 60 shaft 42 being mounted in bearings 43, 43, of the gear housing 44. By this means I provide between the cross rolls and shafts 42 the oscillating coupling shafts 39, whereby the cross rolls are continuously driven during the tilting movement of their frames 5, through the universal joint mechanism described or any other suitable joint providing for universal movement.

65 Each shaft 39 is preferably provided with 65 a supporting yoke 45 engaging the underside of the shaft between collars 46, 46, each yoke being connected by connecting rod or bar 47 with levers 48 pivoted at 49, and having the series of compensating counterweights 50. By this means the shafts 39 are automatically supported at their varying vertical positions. Each driving shaft 42 is provided with one or more toothed gears 51 in driving engagement with pinions 52 of 70 a main drive shaft 53 mounted in suitable bearings in gear housing 44, and also provided with a coupling terminal 54, in universal joint connection with a main driving shaft 55, or otherwise connected with a 75 prime mover.

80 At one side of the cross roll housing, terminating closely adjacent to the pass of the cross rolls and in axial alinement with the working center therebetween and of the 85

5 tube in process, I provide a guide trough 56 which may be an open trough, as shown, adapted to receive the blank and direct it to the pass of the cross rolls, or which may be wholly or partially closed, as desired. Trough 56 is mounted and supported by any suitable means in proper position midway between the shafts 39, and is provided with suitable, preferably adjustable, supporting mechanism, as one or more standards 57 having threaded engagement with holding nuts 58 in frame 59, which may conveniently be made as a portion of the counter-weight supporting frame. It will be understood that at the other side of the pass of the cross rolls, any suitable supporting trough and pusher mechanism may be utilized for supporting and re-introducing the blank or tube in process by its last treated 20 end again to the cross rolls, after they have been again tilted.

25 For the purpose of so pushing the blank into the nip of the cross rolls, I provide at one, and preferably both sides of the cross rolls, as shown in Fig. 2^a, a longitudinally traveling pusher 60 on the end of plunger 61 having a supporting cross head 62 in supporting sliding engagement with an upper beam 63, adapted to maintain the pusher in 30 centralized position at all points longitudinally of its travel. A spring cushioned buffer 63^a is adapted to provide a limiting stop for cross head 62. Plunger 61 extends through stuffing box 64 into a cylinder 65 35 mounted in bearings 66, 66, of the gear housing 44 midway between shafts 42, and in alinement with trough 56, cylinder 65 being provided with suitable actuating fluid connections and valved mechanism, not necessarily herein illustrated or described, whereby the plunger 61 may be actuated positively in one direction or the other for thrusting the blank positively toward the cross rolls and for receding the plunger for 40 another operation, the cylinder being fixedly held in bearing 66 by a stuffing box gland, as shown. Said stuffing box has no necessary function as a fluid packing, and is merely utilized as a convenient means for 45 tightly holding cylinder 65 in place.

50 Mounted centrally below the normal pass of the blank and between the cross rolls 2 is an anvil pedestal or support 67 having an anvil 68 capable of removal and substitution, 55 depending upon the desired bearing surface of the anvil, whereby to support the blank during the reducing operation, immediately below the working position of the cross rolls.

59 For the purpose of providing an upper bearing for the blank, in the same relative position with relation to the cross rolls and blank above such working position, I provide a bearing roller 69, mounted by its journals 70 in bearings 71 of a vertically movable frame 72. Said frame is carried at each

end by supporting pin connections 73 or otherwise, upon vertically reciprocable adjustable cross heads 74, one at each side of the transverse central plane of the cross roll housing, and slidably movable in downwardly depending housing portions 75 of the main upper housing members 12. Roller 69 is of a middle maximum diameter providing a comparatively narrow bearing face, and tapers toward each end. Each of said 75 cross heads is provided with a raising and lowering screw 76 having threaded engagement within a positively holding nut 77, within the housing framing and connected at its lower end, as indicated at 78, with the 80 cross head 74.

85 Each screw or threaded stem 76 is in splined or squared engagement at its upper end, as indicated at 79, with gear wheel 80, each of said gears 80 intermeshing with an 90 actuating pinion 81 on the end of shaft 82 mounted on a middle bearing 83 between the upper housing members 12 and carrying at its lower end a bevel wheel 84. Said bevel wheel is in driving engagement with a similar bevel wheel 85 of shaft 86, which extends across the upper portion of the cross roll housing and is mounted at each end portion within suitable bearings 87 and 88 respectively, and in a suitable bearing 89 at 95 one or both sides of bevel gear 85. Shaft 86 is provided at each end with a bevel gear 90 in driving engagement with a similar bevel 91 on the upper end of shaft 92 carried in bearings 93, 94, at each end portion 100 of the housing frame.

105 Mounted by its hub in lower bearing 94 and freely rotatable around the lower end of shaft 92 is a bevel gear 95 in engagement with a driven bevel gear 96 keyed or otherwise secured to shaft 97 carried in bearings 98, 98, of a cross frame 99. The upper end of the hub of bevel gear 95 is provided with a clutch face adapted to be operatively connected with a vertically movable clutch 100 110 capable of being raised out of engagement by a suitable actuating clutch lever 101, and against the pressure of spring 102, by which it is thrust into clutching operative connection with gear 95, clutch 100 being in splined 115 engagement with shaft 92.

120 Keyed upon-shaft 97 is a pinion 103 which intermeshes at each side with gear wheels 104, 104, each of said gears being in splined engagement with a threaded thrust shaft 105. Said shaft extends through hub 106 of gear 104, which is suitably mounted against longitudinal movement in the main housing, and shaft 105 by its threaded portion engages a nut 107 fixedly mounted within the 125 main housing frame, and is connected, as indicated at 108, with the horizontal slidable frame 7. There being as thus arranged a pair of shafts 105 engaging the slidable frame 7 at each side of its middle portion 130

and thus operating together in one direction or the other, depending upon the operation of the actuating motor, frame 7 may be positively, accurately and gradually moved 5 inwardly or outwardly.

It will be understood that both frames 7, by similar screw mechanism at each side, may be thus moved toward or from each other together, or that either may be adjusted individually.

For the purpose of driving shaft 86 and its connected parts, to-wit, the bearing rollers 69 and frames 7, through the gearing above described, shaft 86 is provided with a 15 worm gear 109 located between bearings 87 and in driven engagement with a worm 110 mounted by its journals 111, 111, in bearings 112 of an upper surrounding coping frame 113. Worm 110 is connected by coupling 20 114 with motor 115, also provided with suitable controlling mechanism, as will be readily understood. By this means it will be seen that shaft 86 may be driven in either direction, either to raise or lower rollers 69, 25 and to advance or recede the adjustable frame 7. Also that the rollers 69 may be adjusted independently of the adjustment of frames 7 by throwing out the clutch 100.

In Figs. 8 to 11 inclusive of the drawings, 30 I have illustrated diagrammatically some of the operations which may be performed by the foregoing mechanism. In Fig. 8 I show the initial or piercing operation when employed, in which piercing point *b* on the end 35 of mandrel bar 61' is maintained in position centrally between the cross rolls 2, 2, and in opposition to the advancing blank *a'*, as is usual in such operations. In Fig. 9 I show a reducing or finishing point *c* similarly 40 mounted on mandrel bar 61' between cross rolls 2, 2, which are adjusted with relation to point *c* to properly reduce the walls of the tube-in-process. In Fig. 10 the tube-in-process is shown as being reduced in diameter 45 without varying the thickness of the walls, by passage between the cross rolls, without the use of a mandrel. In Fig. 11, the tube is passed back between cross rolls 2, 2, and over a point *d* on the end of mandrel 50 bar 61' providing a finishing pass for smoothing the walls and reducing them to the desired gage. Other operations and treatments will readily suggest themselves to those skilled in the art.

55 The operation is carried out by placing the blank in the guide trough 56, when bar 61 and pusher 60 are then advanced, forcing the blank between the cross rolls, they having been previously set to the predetermined desired position, which may be readily determined by a suitable gage. The cross rolls, being located at the proper position for engaging and feeding in the blank to carry it over the piercing point, produce the rough 60 tube, thus performing the first operation, as

is usual in this art. The cross rolls are then reversed in position, changing their inclination with relation to each other, but without changing their direction of rotation, the rolls having been adjusted, if desired, so as to vary their distance apart to the desired degree. The piercing point and mandrel being retracted, the tube is then, by the pusher 60 at the other side of the pass, reversed in direction and re-introduced by its last treated end between the cross rolls for further operation, the tube-in-process being thus treated successively back and forth until ready for the finishing pass. A finishing point may be then mounted on the end of bar 61, 70 depending on the desired finish and intended work of the tube, which may thus be either expanded or reduced in diameter, which operation may be repeated, either with or without a mandrel, as desired, until the tube is 75 completed. By substituting a hollow blank, the initial piercing operation may be dispensed with.

75 The construction of the mechanism and its operation will be readily understood and appreciated from the foregoing description by those skilled in the art. It effects a rapid treatment of the tube in a sufficiently short time to accomplish its reduction without re-heating, while the alternating rolling treatments under the initial heating effectually work and knead the steel in such a manner as to condense and equalize its fibrous nature to effect the best results as to strength and homogeneity.

80 It will be understood that the tube may, if desired, be re-heated at any stage of the operation.

85 The construction, design, proportions or other features of the invention may be variously changed or modified by the skilled mechanician to adapt it to the particular work in hand or to meet any varying conditions of application, within the scope of the appended claims.

90 Having described my invention, what I claim is:

95 1. In a tube rolling mill, a pair of continuously operable cross rolls, a tilting frame for each cross roll having journal bearings therefor, and simultaneously operable gearing operatively connecting said tilting frames for alternating their relative positions together.

100 2. In a tube rolling mill, a pair of continuously operable cross rolls, means for alternating their relative positions, and means for re-introducing a blank by its last treated end to the cross rolls.

105 3. In a tube rolling mill, a pair of continuously operable cross rolls, a tilting frame for each cross roll having journal bearings therefor, simultaneously operable gearing operatively connecting said tilting frames for alternating their relative positions, and

- means for adjusting the cross rolls toward or from each other and maintaining such operative connection.
4. In a tube rolling mill, a pair of continuously operable cross rolls, a tilting frame for each cross roll having journal bearings therefor, simultaneously operable gearing operatively connecting said tilting frames for alternately connecting their relative positions, and means for guiding and forcibly introducing a blank between the cross rolls endwise alternately in opposite directions.
5. In a tube rolling mill, a pair of continuously operable cross rolls, means for alternately connecting their relative positions, means at one side for guiding and introducing a blank between the cross rolls, and means beyond the cross rolls for imparting reversing endwise movement of the blank and reintroducing it to the cross rolls during reversing operation thereof.
6. In a tube rolling mill, a pair of continuously operable cross rolls, means for continuously driving the cross rolls in the same direction during varying positions thereof, means for alternately tilting the cross rolls in opposite directions, and means for introducing a blank to the cross rolls in correspondingly opposite directions.
7. In a tube rolling mill, a pair of continuously operable cross rolls, a tilting frame for each cross roll and a slidable frame for each tilting frame, means for adjusting each slidable frame, tilting frame and cross roll toward or from the other, means for applying confining pressure to the blank between the rolls, actuating gearing for tilting the cross roll frames movable therewith, and a driving shaft in sliding engagement with said gearing.
8. In a tube rolling mill, a pair of continuously operable cross rolls, a tilting frame for each cross roll and a slidable frame for each tilting frame, means for adjusting each slidable frame, tilting frame and cross roll toward or from the other, opposing bearing members embodying an adjustable roll having a middle bearing face and oppositely extending tapered portions for applying confining pressure to the blank between the rolls, actuating gearing for tilting the cross roll frames movable therewith, and a driving shaft in sliding engagement with said gearing.
9. In a tube rolling mill, a pair of cross rolls each arranged at an opposing angle to the other and to an intervening line corresponding to the normal line of travel of the blank and adapted to subject the blank to external compression and feeding action, co-acting means for alternately varying the positions of the cross rolls together and for reducing the distance between them whereby to alternate the longitudinal travel and compression of the blank, and means for re-introducing a blank by its last treated end to the cross rolls.
10. In a tube rolling mill, means for subjecting a blank to oppositely exerted external reducing pressure and diagonally disposed feeding pressure, means for alternately varying the direction of the feeding pressure at each side simultaneously whereby to compress the blank successively in opposite directions, and means for correspondingly re-introducing a blank by its last treated end to the cross rolls.
11. In a tube rolling mill, means for subjecting a blank to internal resisting pressure and to oppositely exerted external reducing pressure and diagonally disposed feeding pressure, means for alternately varying the direction of the feeding pressure at each side simultaneously whereby to compress the blank successively in opposite directions, and means for correspondingly re-introducing a blank by its last treated end to the cross rolls.
12. In a tube rolling mill, means for subjecting a blank to oppositely exerted external reducing pressure and diagonally disposed feeding pressure, means for alternately varying the direction of the feeding pressure whereby to compress the blank successively in opposite directions, and means for guiding and forcibly introducing the blank alternately in opposite directions to said means.
13. A tube rolling mill provided with a pair of cross rolls each having a tilting frame, means for tilting said frames simultaneously in opposite directions embodying gearing movable with the tilting frame and a driving shaft in sliding engagement therewith, and means for continuously driving each of the cross rolls in the same direction.
14. A tube rolling mill provided with a pair of cross rolls each having a tilting frame, means for tilting said frames simultaneously in opposite directions embodying gearing movable with the tilting frame and a driving shaft in sliding engagement therewith, means for adjusting each frame and roll toward or from the other, and means for continuously driving each of the cross rolls in the same direction.
15. A tube rolling mill provided with a pair of cross rolls each having a tilting frame, means for tilting said frames simultaneously in opposite directions, means for adjusting each frame and roll toward or from the other, means for continuously driving each of the cross rolls in the same direction, and means for applying confining pressure to a blank between the cross rolls, and means for re-introducing a blank by its last treated end to the cross rolls.
16. A tube rolling mill provided with a pair of cross rolls each having a tilting frame, means for tilting said frames simul-

taneously in opposite directions, means for adjusting each frame and roll toward or from the other, means for continuously driving each of the cross rolls in the same direction, means for applying confining pressure to a blank between the cross rolls, a guide trough conforming to the normal path of the blank to and from the cross rolls at each side thereof, and a pushing device 10 for each trough in alinement therewith whereby to re-introduce a blank by its last treated end to the cross rolls.

17. In a tube rolling mill, a housing frame, a slidably mounted frame therein at 15 each side of the working pass of the mill, a tilting frame having a rocking bearing in each of said frames, a reducing cross roll journaled in each tilting frame, gearing for adjusting each slidable frame and the tilting frame toward or from the other, gearing for simultaneously actuating both tilting frames in opposite directions, and means for maintaining driving engagement with each cross roll throughout its varying positions 25 embodying a driving shaft in sliding engagement with the gearing for the tilting frames.

18. In combination with the cross rolls having the axes disposed in the same general direction and their supporting and adjusting mechanism; assembled actuating gearing, and substantially parallel spindles having universal joint connections with said assembled gearing and the cross rolls.

19. In combination with the cross rolls having the axes disposed in the same general direction and their supporting and adjusting mechanism; assembled actuating gearing, and substantially parallel spindles 40 having universal joint connections with said assembled gearing and the cross rolls and counterweighted supporting mechanism for the spindles.

20. In combination with the cross rolls 45 having the axes disposed in the same general direction and their supporting and adjusting mechanism; assembled actuating gearing, and substantially parallel spindles having universal joint connections with said assembled gearing and the cross rolls, a guide trough located between said spindles, a pusher bar in alinement with said guide trough, and means for actuating said pusher bar.

21. In a tube rolling mill, a housing frame, a slidably mounted frame therein at each side of the working pass of the mill, a tilting frame having a rocking bearing in each of said frames, a reducing cross roll 60 journaled in each tilting frame, an adjustable bearing roller at one side of the working pass between the cross rolls, gearing for actuating the slidable frame and bearing roller respectively provided with disconnecting clutch mechanism, gearing for actuating

each tilting frame in opposite directions, and means for driving the cross rolls.

22. In a tube rolling mill of the class described, the combination with the cross rolls, 70 tilting frames therefor, slidable frames carrying the rocking frames, a bearing anvil, and an adjustable bearing roller opposing the anvil, of a motor geared with the slidable frames and with the bearing roller, a motor geared with the tilting frames adapted to maintain actuating engagement therewith at their varying positions, and means for driving the cross rolls.

23. In a tube rolling mill of the class described, the combination with the cross rolls, 80 tilting frames therefor, slidable frames carrying the tilting frames, a bearing anvil, and an adjustable bearing roller opposing the anvil, of gearing for actuating the slidable frames, a motor geared with the 85 slidable frame gearing and with the bearing roller, clutch mechanism adapted to connect and disconnect said motor with the slidable frame gearing, a motor geared with the tilting frames adapted to maintain actuating engagement therewith at their varying 90 positions, and means for driving the cross rolls.

24. In a tube rolling mill of the class described, a pair of oppositely arranged 95 slidable frames, a tilting roll frame journaled in each slidable frame, a continuously driven roll mounted in each roll frame, means for propelling each slidable frame back and forth, means for tilting the roll frames simultaneously embodying driving gearing movable with the tilting frames and a driving shaft in sliding engagement therewith, and means for limiting the tilting movement of the roll frames.

25. In a tube rolling mill of the class described, a pair of oppositely arranged 100 slidable frames each having a trunnion bearing and a supporting bearing, a tilting roll frame journaled in the trunnion bearing of each slidable frame having a lower bearing portion engaging the supporting bearing of the slidable frame and having gear teeth, a driven roll journaled in each tilting roll frame, means for propelling each slidable 110 frame back and forth, and means for tilting each roll frame consisting of a worm 115 engaging said teeth, a driving and a driven bevel gear therefor, and a driving shaft in sliding engagement with said bevel gear.

26. In a tube rolling mill of the class described, a pair of oppositely arranged 120 slidable frames each having a trunnion bearing, a supporting bearing and lateral limiting abutments, a tilting roll frame journaled in the trunnion bearing of each slidable frame having a lower bearing portion engaging the supporting bearing of the slidable frame and lateral bearings adapted to engage said abutments, a driven roll journaled in each 125 130

tilting roll frame, means for propelling each
slidable frame back and forth, and means
for tilting the roll frames simultaneously
consisting of gearing mounted to travel with
5 the slideable frames, and a driving shaft
in sliding engagement therewith.

In testimony whereof I hereunto affix my
signature in the presence of two witnesses.

RICHARD E. BROCK.
